[57] CLAIM

The ornamental design for a combined watch and handbag, as shown and described.

DESCRIPTION

FIG. 1 is a front elevational view of a combined watch and handbag showing my new design;

FIG. 2 is a rear elevational view thereof;

FIG. 3 is a side elevational view, the opposite side being a mirror image thereof;

FIG. 4 is a top plan view thereof; and,

FIG. 5 is a bottom plan view thereof.

The surface texture on the serpent head clasps is continuous throughout the drawing.
